CLAIM

The ornamental design for a smoking supply package assembly, as shown and described.

DESCRIPTION

FIG. 1 is a perspective view of a smoking supply package assembly showing my new design, the box being in a closed position;

FIG. 2 is a perspective view of the box illustrated in FIG. 1 in an open position;

FIG. 3 is a right side elevational view of the box illustrated in FIG. 1 in the open position;

FIG. 4 is a left side elevational view of the box illustrated in FIG. 1 in the open position;

FIG. 5 is a front elevational view of the box illustrated in FIG. 1 in the open position;

FIG. 6 is a back elevational view of the box illustrated in FIG. 1 in the open position;

FIG. 7 is a top plan view of the box illustrated in FIG. 1 in the open position;

FIG. 8 is a bottom plan view of the box illustrated in FIG. 1 in the open position;

FIG. 9 is a perspective exploded view along line 10 of the smoking supply package assembly showing my new design, the assembly including the box, a container, a lighter, and two tubes;

FIG. 10 is a section view of the box of the assembly illustrated in FIG. 9;

FIG. 11 is a perspective view of the container of the smoking supply package assembly showing my new design, the container being in an open position;

FIG. 12 is a perspective view of the container illustrated in FIG. 11 in a closed position;

FIG. 13 is a front elevational view of the container illustrated in FIG. 11 in the closed position;

FIG. 14 is a back elevational view of the container illustrated in FIG. 11 in the closed position;

FIG. 15 is a right side elevational view of the container illustrated in FIG. 11 in the closed position;

FIG. 16 is a left side elevational view of the container illustrated in FIG. 11 in the closed position;

FIG. 17 is a top plan view of the container illustrated in FIG. 11 in a closed position;

FIG. 18 is a bottom plan view of the container illustrated in FIG. 11 in a closed position;

FIG. 19 is a perspective view of the lighter of the smoking supply package assembly showing my new design;

FIG. 20 is a left side elevational view of the lighter illustrated in FIG. 19;

FIG. 21 is a right side elevational view of the lighter illustrated in FIG. 19;

(Continued)

FIG. 22 is a front elevational view of the lighter illustrated in FIG. 19;

FIG. 23 is a back elevational view of the lighter illustrated in FIG. 19;

FIG. 24 is a top plan view of the lighter illustrated in FIG. 19; and,

FIG. 25 is a bottom plan view of the lighter illustrated in FIG. 19.

In the drawings, the broken lines depict portions of the smoking supply package assembly that form no part of the claimed design.
